**APPARATUS FOR OPERATING ELECTRIC
DISCHARGE DEVICES**
Walter F. Powell, Jr., Danville, Ill., assignor to General
Electric Company, a corporation of New York
Filed July 23, 1962, Ser. No. 211,555
17 Claims. (Cl. 315—151)

This invention relates generally to apparatus for operating electric discharge devices such as fluorescent lamps and more particularly, it relates to an improved apparatus for operating such devices.

It is an essential requirement of an apparatus used to operate electric discharge devices that the current supplied to the electric discharge device be regulated. Unless the current supplied to the electric discharge device is regulated, the lamp current in the lamp becomes excessive and the lamp will destroy itself because of its inherent negative resistance characteristic.

Heretofore, passive ballasting systems have been used to operate electric discharge devices such as fluorescent lamps or mercury vapor lamps. In such passive systems a ballasting means, usually a reactive element, is employed to achieve a balance between the energy available at the source and the energy required to operate the electric discharge lamp. In a commonly used ballasting system, the reactive element, the driving voltage source and the electric discharge lamp are associated in a series loop arrangement. As the lamp current builds up because of the negative resistance characteristic of the device, the current through the reactive element builds up causing an increase in the voltage drop across the reactive element. Consequently, the voltage drop across the lamp decreases since the sum of the voltage drops in the lamp circuit must be equal to the driving voltage which is fixed. As the voltage across the series reactor increases, the lamp current diminishes. In this manner, the ballasting element passively regulates the current supplied to the lamp to provide a ballasting action.

A disadvantage of a conventional passive ballast system is that the volt-ampere requirements of the reactive elements in the system must be relatively high and also the peak energy stored in the reactive elements must be relatively high in order that the ballasting action can be effected with satisfactory regulation and stability. To provide satisfactory regulation when the supply voltage varies plus or minus ten percent, it is necessary that the ballasting volt-ampere characteristic intersect the normal volt-ampere characteristic of the electric discharge lamp at a sufficiently steep angle. It will be understood that in passive ballast systems supply voltages two or three times as great as the lamp operating voltage are usually required to provide a satisfactory ballasting characteristic. It is desirable, therefore, to reduce the volt-ampere requirements of the ballast while achieving satisfactory regulation and stability.

Accordingly, it is a general object of the invention to provide an improved apparatus for operating one or more electric discharge lamps.

A more specific object of the invention is to provide an improved apparatus for operating electric discharge lamps that is readily adaptable to control by feedback means.

It is another object of the invention to provide an improved apparatus for operating electric discharge lamps wherein the volt-ampere requirements of the apparatus are not relatively high.

A still further object of the invention is to provide an improved apparatus for operating fluorescent lamps with relatively less peak energy stored in the reactive elements employed for ballasting.

In accordance with one aspect of my invention, I have provided an improved apparatus for operating one or

2

more electric discharge lamps in which a control means for varying the energy supplied from a power source dynamically achieves an approximate balance between the energy supplied by the power source and the energy required for operation of the electric discharge lamp or lamps by switching the supply energy from one predetermined level to another. A feedback circuit is coupled with control means to activate the control means and to vary the energy supplied to the lamp in response to a feedback signal. The feedback signal may be proportional to the lamp current or may have some other functional relationship to the current or other parameter.

In a form of my invention, a dynamic balance is achieved between the energy supplied at the input of the apparatus and the energy required for lamp operation by a switching arrangement in which a switching means is driven in response to a feedback signal to cause an impedance element to be effectively cut in and out of serial connection with the lamp and thereby regulate the energy supplied to the lamp.

According to another form of my invention, I provide a control means for varying the energy supplied from the source which includes a transformer in conjunction with a switching arrangement wherein a portion of the transformer secondary is repetitively switched in and out of the circuit to better dynamically balance the source energy with the energy required for lamp operation. The switching action is controlled by a feedback circuit which is activated in response to a feedback signal indicative of a lamp operating condition.

In accordance with my invention, the electric discharge of the lamp or lamps is stabilized by the dynamic control exercised by the apparatus over the source energy to provide the energy required by the lamp. Preferably, the amount of energy supplied to a lamp is controlled and regulated in response to changes in the parameters sensed or detected by the feedback circuit. By way of illustration, the feedback circuit may sense such parameters as lamp current, light output, lamp voltage, lamp power, lamp arc stream temperature, or combinations of such parameters to provide a suitable feedback signal for controlling the operation of a lamp.

The subject matter which I regard as my invention is particularly pointed out and claimed in the concluding portion of this specification. My invention, however, both as to its structure and manner of operation, together with further objects and advantages thereof, may be best understood by reference to the following description taken in conjunction with the accompanying drawings in which:

FIGURE 1 is a schematic illustration of one embodiment of the invention wherein the control means in accordance with the invention is driven in response to a feedback signal that is proportional to the lamp current;

FIGURE 2 is a schematic illustration corresponding to the embodiment of the invention shown in FIGURE 1 wherein the control means is driven in response to a feedback signal that is proportional to the light output of an electric discharge lamp;

FIGURE 3 is a schematic circuit diagram of the bilateral switch shown in block form in the illustration of FIGURE 1;

FIGURE 4 is a schematic circuit diagram of another embodiment of my invention wherein the electric discharge lamp is operated with a unidirectional current;

FIGURE 5 is a schematic illustration of an alternative embodiment of the invention for operating electric discharge lamps with an alternating current supply; and

FIGURE 6 is a schematic diagram of the bilateral switches and the feedback control shown in block form in the illustration of FIGURE 5.

Referring in more detail to the FIGURE 1 of the

drawing, I have shown therein an apparatus, generally identified by reference numeral 10, for operating an electric discharge lamp 11. The components of the apparatus 10 are shown enclosed in a dashed rectangle. A pair of input terminal leads 12, 13 are provided for connection to a suitable alternating current supply. The output of the apparatus 10 is applied to the electric discharge lamp 11 by output leads 14 and 15.

In accordance with one form of the invention, a bilateral switch 16 is driven in response to a feedback signal supplied at the feedback leads 17 and 18 connected across a shunt resistor R₂. The bilateral switch 16 is repetitively switched to an open position (high impedance state) and a closed position (low impedance state) in each half cycle of the alternating current supply to dynamically balance the source energy with the energy required to operate the electric discharge lamp 11 connected across the output leads 14, 15. When the bilateral switch 16 is driven to the open position, an impedance element, such as the resistor R₁ used in the illustrated exemplification of the invention, is effective in the lamp circuit. The voltage applied to lamp 11 does not change immediately since the voltage across the inductor L₁ assumes a polarity that is additive with respect to the supply voltage. As energy is released from the inductor L₁ and the current decreases toward a lower steady-state level, the lamp voltage momentarily increases. Essentially, the actuation of the bilateral switch 16 varies the impedance load in the circuit with the lamp voltage remaining nearly constant.

When lamp 11 is operated by the apparatus 10, the current is kept in continuous transition between two steady-state current levels, one of which by itself is too high and the other too low. An inductor L₁ is provided to introduce a small amount of inductance in the circuit to control the rate at which the transition proceeds between the two steady-state levels. It will be appreciated that the inductor L₁ is a relatively small high frequency inductor and would not provide sufficient reactance to control the operation of the electric discharge lamp 11 in accordance with the conventional practice. In the exemplification of the invention, the inductor L₁ had an inductance of approximately 30 millihenries.

In the circuit diagram of FIGURE 2, I have illustrated an apparatus 20 wherein a bilateral switch 21 is activated in response to a feedback signal from a photoelectric cell 22 disposed near the electric discharge lamp 11 to sense the light output and regulate the energy supplied to lamp 11 in response to the variations in the light output. The feedback signal from the light sensitive cell 22 is supplied to the bilateral switch 16 by leads 23, 24.

The apparatus 20 as shown in FIGURE 2 is generally similar to the apparatus 10 of FIGURE 1. Accordingly, I have used the same reference numerals to identify the corresponding parts thereof. The shunting impedance element R₁ is connected in shunt across the bilateral switch 21. To control the rate of change of the rapid excursions of current, a high frequency inductor L₁ is connected in series with the bilateral switch 21.

The operation of the apparatus 10 shown in FIGURE 1 and the apparatus 20 as shown in FIGURE 2 will now be described. During each alternation of the power supply, the bilateral switches 16 and 21 are driven repetitively from a normally closed position to an open position in response to a feedback signal. The repetitive switching action causes the energy supplied at the output leads 14 and 15 to be dynamically varied to control the operation of lamp 11. When the bilateral switch 16 or 21 is in its normally closed position or in the open position, energy is supplied from the power source to output leads 14, 15.

Taking an arbitrary positive half cycle when the voltage at input terminal lead 12 is positive and the bilateral switch is closed, the path of current flow is from input terminal lead 12, through the inductor L₁, the bilateral switch, output lead 14, lamp 11, output lead 15 and input

terminal lead 13. It will be noted that when the bilateral switch is driven to the open position the current from the power supply is diverted through the impedance element R₁, causing the current to decrease to the lower steady-state value. Thus, in both switching modes energy is being continuously supplied to the electric discharge lamp 11 from the power source and is dynamically balanced to meet the ballasting and operational requirements of the electric discharge lamp 11. In the apparatus 10 of FIGURE 1, the switching action is controlled in response to a feedback signal determined by lamp current. However, in apparatus 20 shown in FIGURE 2, the bilateral switch 21 is driven in response to a feedback signal provided by the light sensitive cell 22.

10 Bilateral switches of the type which may be used in the practice of this invention are fast acting switches, such as transistors or silicon controlled rectifiers, which can be activated at switching rates above several hundred switchings per second. Preferably, switching rates between 15 1000 and 50,000 switchings per second may be employed in the practice of the invention.

15 Referring now to FIGURE 3, I have illustrated therein a schematic circuit diagram of the bilateral switch employed in the embodiment of the invention illustrated in FIGURE 1. The switching action is performed by a transistor switch Q₁, a power PNP transistor, that is driven by a bistable flip flop circuit controlled by a feedback signal applied at leads 17, 18.

20 The bilateral operation of the transistor switch Q₁ is achieved by connecting the transistor switch Q₁ in a bridge arrangement employing four diodes D₁, D₂, D₃ and D₄. It will be seen that during the positive alternation of the alternating current supply when the voltage at input terminal lead 12 is positive, diodes D₁ and D₂ are forward 25 biased and the diodes D₃ and D₄ are reverse biased, and a forward bias is applied across diodes D₃ and D₄ causing these latter two diodes to conduct current. Thus, 30 during the negative alternation a path for current flow is provided from lead 14 through the diode D₃, transistor switch Q₁ and diode D₄ to input terminal lead 12.

35 The bistable flip flop circuit includes a tunnel diode TD₁ and control transistors Q₂ and Q₃. Base drive for transistors Q₁, Q₂ and Q₃ and bias current for the tunnel diode TD₁ is provided by connecting terminals 25 and 26 to a negative and positive control supply. Resistor R₃ connected with terminal 25 limits the base drive current for transistor Q₁ and resistor R₄ sets the bias current for the tunnel diode flip flop. In order to reduce the turn-off time, resistors R₅ and R₆ are connected in circuit with the 40 base electrodes of transistors Q₁ and Q₂. Diodes D₅ and D₆ connected to the base electrode of transistor switch Q₁ prevent the voltage drop developed across the 45 collector and emitter electrodes of transistor Q₂ when transistor Q₂ is switched on, from driving the base-emitter junction of the transistor switch Q₁ to a conducting state. A Zener diode D₇ connected in shunt across the collector and emitter of electrode of transistor switch Q₁ protects 50 the transistor against transient overvoltages.

55 Essentially, the switching frequency of the transistor switch Q₁ is determined by the rate at which the tunnel diode TD₁ is switched to a high voltage state and reset by the pulses induced across secondary winding S₁ of a pulse transformer T₁. The bias supplied to the tunnel diode TD₁ through resistor R₄ is just sufficient to maintain the tunnel diode TD₁ near its peak point value. When a negative pulse is induced across the secondary winding S₁, tunnel diode TD₁ is switched to its high voltage state. Capacitor C₁ is connected in circuit with the secondary winding S₁ in order to provide for D.C. isolation and pulse coupling of the secondary winding S₁ with the bistable flip flop circuit.

60 To provide the pulses required to activate the flip flop circuit from one state to another, a pair of tunnel diode

circuits are used and alternately come into play as the supply voltage swings positive and negative. During the positive alternation the tunnel diode circuit, which includes steering diode D_9 , tunnel diode TD_2 , resistor R_7 , and primary winding P_1 of pulse transformer T_1 , comes into play. In the negative half cycle, the companion tunnel diode circuit, which includes the steering diode D_8 , tunnel diode TD_3 , resistor R_8 and the primary winding P_2 , comes into play. The resistors R_7 and R_8 prevent ringing in the tunnel diode circuits, and the feedback resistor R_9 limits the feedback current supplied to the tunnel diode circuits. Also, without the resistor R_9 the tunnel diodes TD_2 , TD_3 would assume the potential across leads 17 and 18 and a switching action would not occur.

It will be appreciated that the feedback leads 17 and 18 may be connected in circuit with various sensing elements which will provide a suitable feedback signal for controlling the switching action of the transistor switch Q_1 . For example, the input signal may be provided by a feedback circuit which senses such parameters as line current, lamp voltage, lamp power, line voltage, arc temperature, lighting illumination levels or combinations of these parameters. Although in FIGURES 1 and 2 the feedback signal provides a control that is responsive to the lamp current and light output, it will be understood that the feedback means may sense other parameters and control the operation of the lamp in response thereto. Preferably, the bilateral switch 16 may be driven in response to a lamp current feedback in conjunction with other feedback signals such as signals indicative of the light output or device temperature.

Referring now to FIGURES 1 and 3, the operation of the bilateral switch 16 will now be more fully explained. During the open circuit condition of the lamp 11, the voltage of the alternating current source is essentially applied across the output leads 14 and 15. The bilateral switch 16 will remain in a closed position until the electric discharge lamp 11 ignites.

It will be understood that a starting aid circuit may be used to aid in the starting of the electric discharge lamp 11. Where an auxiliary starting circuit is used, it is generally possible to start an electric discharge lamp at a lower potential level. In a well-known starting aid arrangement, a conductive plate, which is usually the lamp fixture, is disposed in proximity to the electric discharge lamp so that a starting aid potential is initially applied between a lamp electrode and the conductive plate to aid in initiating the electric discharge in the vicinity of the electrode. Although I have not shown such auxiliary starting aid arrangements in the embodiments of my invention, it will be readily understood that such auxiliary starting aid arrangements are readily adaptable for use in conjunction with the apparatus of the invention.

At the start of an arbitrary half cycle of the alternating power supply when lamp 11 is ionized and the voltage is positive and increasing, the current through the normally closed bilateral switch 16 and through the shunt resistor R_2 begins to increase. The voltage across the shunt resistor R_2 is such that the right end is positive with respect to the left end, and a current flows through the feedback resistor R_9 of the bilateral switch 16. Since steering diode D_9 is now biased in a forward direction, current flows in two loops, one of which includes the tunnel diode TD_2 , and the other of which includes the resistor R_7 and the primary winding P_1 . When this feedback current builds up to the peak point value of tunnel diode TD_2 , tunnel diode TD_2 switches to a high voltage state. The increased impedance of tunnel diode TD_2 causes a diversion of current to the primary winding P_1 , and a negative pulse is induced in the secondary winding S_1 of pulse transformer T_1 .

A negative pulse across the secondary winding S_1 causes tunnel diode TD_1 to switch to its high voltage state. When tunnel diode TD_1 is switched to a high

voltage state, base drive is applied to the base electrodes of transistors Q_2 and Q_3 , and they are switched into conduction. When transistors Q_2 and Q_3 conduct, the base drive is removed from transistor switch Q_1 and consequently, the transistor switch Q_1 is turned off.

When transistor switch Q_1 is turned off, current from the power supply now flows through the impedance element R_1 thereby causing a decrease in the energy supplied at the output leads 14 and 15. As bilateral switch 16 is opened and closed, energy supplied to the lamp is alternately switched from one level to another level back and forth. The inductor L_1 controls the rate of change of the energy as the switching action causes excursions of energy from one energy level to another.

When the impedance element R_1 is effectively placed in the lamp circuit, this is accompanied by a decrease in lamp current and in the voltage drop across the shunt resistor R_2 . Consequently, the current through the feedback resistor R_9 decreases, and when the voltage across the tunnel diode TD_2 reaches the valley point value, the tunnel diode TD_2 is reset to its low voltage state. As a result, current is now diverted from the primary winding P_1 , and this change in current produces a change in the flux linking the secondary winding S_1 causing a positive pulse to be induced in the secondary winding S_1 . The positive pulse across secondary winding S_1 causes the tunnel diode TD_1 to be reset to its low voltage state. At the instant tunnel diode TD_1 is reset to the low voltage state, base drive is diverted from both transistors Q_2 and Q_3 to cause them to be switched off. Base drive is now applied to the base electrode of the transistor switch Q_1 . Consequently, transistor switch Q_1 is driven into conduction, and bilateral switch 16 is now closed. This switching action continues during the positive half cycle so long as the current remains at a sufficient level to activate the tunnel diode TD_2 .

During the negative alternation of the alternating current supply, the bilateral switch 16 is closed at the start of the cycle since the voltage is insufficient to activate the tunnel diode TD_3 . An increasing negative current now flows in the loop which includes tunnel diode TD_3 , the primary winding P_2 of pulse transformer T_1 and the resistor R_8 . When the current reaches the peak point value of tunnel diode TD_3 , the tunnel diode TD_3 is switched into a high voltage state. This causes a diversion of current to the primary winding P_2 , and a negative pulse is induced in the secondary winding S_1 . As in the positive half cycle, the negative pulse will switch on transistors Q_2 and Q_3 and cause the base drive to be diverted from the base electrode of the transistor switch Q_1 . Thus, the bilateral switch 16 is now turned off and the impedance element R_1 is effective in the lamp circuit to provide a reduction in the energy level supplied to the lamp. This is accompanied by the decrease in the voltage drop across the shunt resistor R_2 . When the voltage across the shunt resistor R_2 reaches a point where the voltage across the tunnel diode TD_3 is at its valley point value, the tunnel diode TD_3 is reset to its low voltage state. Current from the primary winding is now diverted to the tunnel diode TD_3 , and this change in the flow of current through the primary winding P_2 produces a positive pulse across the secondary winding S_1 . As previously described, a positive pulse across the secondary winding S_1 will cause the transistor switch Q_1 to be switched on. This switching action repeats itself during the negative half cycle so long as the voltage across the shunt resistor R_2 is maintained at a sufficient level to activate the tunnel diode TD_3 .

It will be apparent that during each alternation of the power supply the bilateral switch 16 is repetitively opened and closed in response to a feedback signal that is functionally related to the lamp current. The switching action will continue as long as the feedback signal is sufficient to activate the tunnel diodes TD_2 and TD_3 .

The operation of the apparatus 20 shown in FIGURE

2 is essentially similar to the operation of apparatus 10 of FIGURE 1. The bilateral switch 21 is repetitively opened and closed in each half cycle to provide controlled excursions of energy from one predetermined level to another and thereby to provide the operating voltage required to maintain a substantially constant light output and also to regulate the amount of energy supplied to the lamp 11. As the energy level across the output leads 14, 15 of the apparatus 20 increases, the instantaneous light output of the lamp 11 also increases and the feedback signal to the bilateral switch 21 increases. The increasing feedback signal will cause the bilateral switch 21 to switch to an open position. Also, when the light output instantaneously decreases, the feedback signal decreases, and bilateral switch 21 is driven to its closed position. It was found that a repetitive switching action regulated in response to a feedback signal produced by variations of the lamp light output will control the operation of the lamp 11. A principal advantage of such a feedback arrangement is that an electric discharge lamp can be operated at a substantially constant light output during its normal life.

In FIGURE 4, I have illustrated an embodiment of my invention in which an electric discharge lamp 11 is operated with a unidirectional or unipolar voltage output across output leads 31 and 32. A pair of input terminal leads 33, 34 are provided for connection to a suitable D.C. power source (not shown). As in the other embodiment of the invention, the energy applied at the input leads 33, 34 is dynamically balanced by the repetitive action of the transistor switch Q₄ to meet the operating requirements of lamp 11. As transistor switch Q₄ is repetitively driven from a normally closed position to an open position, the electric discharge lamp 11 is operated by alternately increasing and decreasing excursions of energy from the power source. The energy supplied to lamp 11 by these excursions is sufficient to operate the lamp.

A resistor R₁₁ is connected across the base and emitter electrodes of the transistor switch Q₄ to reduce the turn-off time of the transistor switch Q₄ and thereby increase its switching speed. A diode D₁₀ is connected in circuit with the base electrode of the transistor switch Q₄ to prevent the voltage drop across the collector and emitter electrodes of transistor Q₅ when transistor Q₅ conducts from driving the base-emitter junction of transistor switch Q₄ to a conducting state. The PNP transistor Q₅, a tunnel diode TD₄, a shunt resistor R₁₂ and a feedback resistor R₁₄ comprise a feedback controlled driver for the transistor switch Q₄. Base drive for the transistor switch Q₄ is provided through a resistor R₁₃ by connecting terminal 35 in circuit with a suitable negative D.C. bias supply. A feedback resistor R₁₄ limits the feedback signal supplied to the tunnel diode TD₄. A terminal 36 is provided for connection to a positive bias source.

The transistor switch Q₄ is normally in a closed position because the tunnel diode TD₄ is normally in a low voltage state. It will be noted that when tunnel diode TD₄ is in a low voltage state, the transistor Q₅ is in a high impedance state, and base drive is applied from the negative bias supply through resistor R₁₃ and diode D₁₀ to the base electrode of the transistor switch Q₄. A high frequency inductor L₂ is provided to control the rate of current excursions resulting from the repetitive switching action of the transistor switch Q₄.

Operation of apparatus 30 is initiated by connecting the input terminal leads 33 and 34 to a negative and positive side of the direct current power supply, respectively. During the open circuit condition of the electric discharge lamp 11, the potential of the D.C. source is essentially applied across the lamp 11. When lamp 11 has ignited, the path of current flow is from the positive terminal 34, to the output terminal 32, the electric discharge lamp 11, output lead 31, the inductor L₂, the shunt resistor R₁₂, the transistor switch Q₄ and to input

terminal lead 33. As this current builds up, the voltage drop across the shunt resistor R₁₂ also builds up, and when the feedback current through resistor R₁₄ reaches the peak point value of the tunnel diode TD₄, the tunnel diode TD₄ switches to a high voltage state. Transistor Q₅ is driven into conduction and removes the base drive from the transistor switch Q₄. Transistor Q₄ is, therefore, switched to an open position or high impedance state. Impedance element R₁₀ is now effective in the lamp circuit and causes the energy supplied to lamp 11 to decrease. Also, the voltage across the shunt resistor R₁₂ decreases, and when the voltage across the tunnel diode TD₄ reaches its valley point value, the tunnel diode TD₄ is reset to a low voltage state. As a result, transistor Q₅ is switched off and base drive is applied to the base electrode of the transistor switch Q₄ to switch it to the closed position or low impedance state. Accordingly, the energy level supplied to the electric discharge lamp 11 now rises and the switching cycle repeats itself. The electric discharge lamp 11 is operated with a varying D.C. current controlled by a feedback signal determined by the lamp current.

Referring now to FIGURE 5, I have shown illustrated therein an embodiment of my invention generally identified by reference numeral 40, in which the output of a transformer T₂ is dynamically switched to approximately match the operating requirements of a pair of lamps 1 and 2 by a pair of bilateral switches 41 and 42 driven by a feedback control 43 receiving a feedback signal from the lamp circuit. A pair of input terminal leads 46 and 47 are provided for connection with a suitable alternating current power supply. In apparatus 40, the input voltage is applied across a primary winding P₃ of the transformer T₂. A pair of secondary windings S₂ and S₃ are inductively coupled with the primary winding P₃ on a magnetic core 48. The transformer T₂ must have a low leakage reactance and may preferably be bifilar wound. It will be noted that bilateral switch 42 is connected at one end to a tap 49 by electrical lead 50 and at the other end it is joined with the bilateral switch 41 by leads 51 and 52.

It will be seen that when the bilateral switch 42 is closed, bilateral switch 41 is synchronously opened. During this switching mode, only the voltage across the secondary winding S₂ is applied across lamps 1 and 2. However, when the bilateral switch 42 is opened and bilateral switch 41 is closed, the voltage across the secondary windings S₂ and S₃ is applied across the lamps 1, 2 and inductor L₃. In essence, the bilateral switches 41 and 42 function as a single pole double throw switch to alternately connect the secondary winding S₂ and the secondary windings S₂ and S₃ into the lamp circuit. The inductor L₃ is a small high frequency inductor and provides a small voltage drop between the instantaneous secondary voltage of transformer T₂ and the instantaneous lamp voltage.

Bilateral switches 41, 42 are connected in circuit with the feedback control 43 by means of the connecting leads 53, 54 and 55, 56. A feedback signal is supplied to the feedback control 43 by the electrical leads 57, 58 connected across a shunt resistor R₁₅.

Referring now to FIGURE 6, I have illustrated therein a schematic circuit diagram of the bilateral switches 41, 42 and the feedback control 43 corresponding to the blocks 41, 42 and 43 as shown in the diagram of FIGURE 5. Referring more specifically to the feedback control 43, it will be seen that a feedback signal is supplied to the feedback control 43 through leads 57 and 58, a feedback resistor R₁₆ and to the steering diodes D₁₁ and D₁₂. Steering diode D₁₁ is forward biased during the positive half cycle of the alternating current supply while diode D₁₂ is forward biased during the negative half cycle.

It will be noted that primary winding P₅ of a pulse transformer T₃ and a primary winding P₆ of a pulse transformer T₄ are connected in parallel with each other

in a loop which includes a resistor R_{17} and a tunnel diode TD_5 . Similarly, primary windings P_4 and P_7 of the pulse transformers T_3 , T_4 are connected in parallel with each other in a loop which includes a resistor R_{18} and a tunnel diode TD_6 . Since the steering diode D_{11} conducts during the positive half cycle of the alternating current supply, the circuits which include tunnel diode TD_5 and the primary windings P_5 , P_6 are energized. In the negative half cycle, diode D_{12} conducts and allows current to flow to the circuits which include tunnel diode TD_6 and primary windings P_4 and P_7 .

The opening and the closing of the bilateral switches 41 and 42 are synchronized in each half cycle by the pulses generated across the secondary windings S_4 and S_5 .

A negative pulse across the secondary winding S_4 will cause the normally closed bilateral switch 41 to be driven to an open position and a negative pulse across the secondary winding S_5 will cause the normally open bilateral switch 42 to be activated to a closed position. The resistors R_{17} and R_{18} were provided to prevent ringing in the tunnel diode loops.

Referring now more specifically to the bilateral switches 41, 42 as shown in FIGURE 6, the schematic circuit diagrams of these switches will now be more fully described. The switching action of transistor switch Q_6 of the bilateral switch 41 is controlled by a bistable flip flop circuit which is comprised of a PNP transistor Q_7 and a tunnel diode TD_7 . The switching action of the transistor switch Q_8 of bilateral switch 42 is controlled by a bistable flip flop circuit which includes the PNP transistors Q_9 and Q_{10} and a tunnel diode TD_8 . A Zener diode D_{14} and the resistors R_{21} , R_{28} control the bias conditions for tunnel diode TD_8 . Resistors R_{20} , R_{22} and R_{23} limit base drive current to transistors Q_6 , Q_9 and Q_8 , respectively. Similarly, Zener diode D_{13} and resistors R_{19} and R_{27} control the bias conditions for the tunnel diode TD_7 of bilateral switch 41. Zener diodes D_{15} and D_{16} protect the transistor switches Q_6 and Q_8 against excessive transient voltages.

A capacitor C_2 is connected in circuit with the secondary winding S_4 of the pulse transformer T_3 to provide for D.C. isolation and pulse coupling of the secondary winding S_4 with the driver circuit. Also, a capacitor C_3 is connected in circuit with the secondary winding S_5 and performs the same function for the bilateral switch 42. Resistors R_{24} , R_{25} and R_{26} reduce the turn-off time of the transistors Q_6 , Q_9 and Q_8 . Diodes D_{17} , D_{18} and D_{19} are connected respectively with the base electrodes of transistors Q_6 , Q_9 and Q_8 . Diode D_{17} prevents the voltage developed across the collector and emitter electrodes of transistor Q_7 when transistor Q_7 conducts from driving the base emitter junction of transistor switch Q_6 to a conducting state. Similarly, diode D_{18} prevents the voltage developed across the collector and emitter electrodes of transistor Q_{10} from driving transistor Q_9 . Diode D_{19} performs a similar function for transistor switch Q_8 .

The bilateral switching action in bilateral switch 41 is provided by a bridge arrangement which includes the diodes D_{20} , D_{21} , D_{22} and D_{23} . It will be seen that diodes D_{20} and D_{21} provide a path through transistor switch Q_6 for current flow during the positive half cycle, and diodes D_{22} and D_{23} provide a path for current flow through the transistor switch Q_6 during the negative half cycle. Similarly, in bilateral switch 42, diodes D_{24} and D_{25} provide a path through transistor Q_{10} during the positive half cycle and diodes D_{26} and D_{27} provide a path for current flow through transistor switch Q_8 during the negative half cycle.

Having reference now to FIGURES 5 and 6, the operation of the apparatus 40 will now be more fully described. When the primary winding P_3 of transformer T_2 is initially energized, bilateral switch 41 is in a closed position and bilateral switch 42 is in an open position. Hence, the combined voltage across the secondary wind-

ings S_2 and S_3 is applied across the electric discharge lamps 1, 2 and inductor L_3 . When lamps 1 and 2 are ignited, current flows in lamp circuit.

Assuming that the voltage across the shunt resistor R_{15} is such that the right end of the resistor R_{15} , as seen in FIGURE 5, is positive, tunnel diode TD_5 will be switched to a high voltage state when the current reaches the peak point value. At the instant tunnel diode TD_5 is switched, current is diverted to the primary windings P_5 and P_6 and a negative going pulse is induced in the secondary windings S_4 and S_5 . As a consequence, tunnel diodes TD_7 and TD_8 of the bilateral switches 41, 42 are switched to their high voltage state.

It will be noted that when tunnel diode TD_7 is in a high voltage state, transistor Q_7 is driven to conduction, and base drive is removed from transistor switch Q_6 to turn it off. Simultaneously, as tunnel diode TD_8 of the bilateral switch 42 is switched into a high voltage state, transistor Q_{10} is switched on. As a consequence, base drive is removed from transistor Q_9 to turn it off and cause transistor switch Q_8 to be driven to conduction.

In this switching mode, as bilateral switch 41 is opened, bilateral switch 42 is synchronously closed. Thus, only the potential across the secondary winding S_2 is essentially applied across lamps 1 and 2. It will be seen that the path of current flow during this switching mode is in a loop which includes the secondary winding S_2 , lead 50, bilateral switch 42, lead 52, the inductor L_3 , output lead 44, lamps 1 and 2, output lead 45 and the shunt resistor R_{15} . The decreased potential applied across the lamps 1 and 2 results in a decline of the instantaneous lamp current.

When the voltage drop across the shunt resistor R_{15} drops to a point where the current through the tunnel diode TD_5 reaches the valley point value, the tunnel diode is reset to its low voltage state, and now current is diverted from the primary windings P_5 and P_6 . This change in current flow causes a positive pulse to be induced across the secondary windings S_4 and S_5 . The positive pulse across the secondary windings S_4 and S_5 causes the tunnel diodes TD_7 and TD_8 , respectively, to be reset to their low voltage state. Consequently, the bilateral switch 41 is restored to its normally closed position and bilateral switch 42 is synchronously restored to its normally open position.

During this switching mode, the path of current flow is in a loop which includes secondary windings S_2 and S_3 , bilateral switch 41, lead 51, the inductor L_3 , output lead 44, lamps 1 and 2, output lead 45 and shunt resistor R_{15} . The feedback signal supplied to the feedback control 44 is now increasing, and when this signal reaches the peak point value of tunnel diode TD_5 , the bilateral switch 41 is again switched to the open position and bilateral switch 42 is synchronously driven to a closed position. This switching cycle repeats itself during the positive half cycle of the alternating current supply so long as the voltage drop across the shunt resistor R_{15} is sufficient to drive the tunnel diodes TD_5 and TD_6 to a high voltage state.

During the negative alternation of the power supply, the circuit loops which include tunnel diode TD_6 , the primary windings P_4 , P_7 and the resistor R_{18} , come into play, and a negative voltage signal induced across the secondary windings S_4 , S_5 will synchronize the switching action of the bilateral switches 41 and 42 in substantially the same manner as during the positive alternation. As bilateral switches 41 and 42 are synchronously switched from a closed to an open position, the energy supplied to the lamps 1, 2 is alternately varied between one level and another in response to the feedback signal. The transformer T_2 and the driven bilateral switches 41, 42 serve as a control means to dynamically balance the energy at the source to provide the energy required for operation of the lamps 1, 2 in response to the feedback signal supplied by the feedback control 43.

Referring now more particularly to the schematic

circuit diagrams of the bilateral switches 41 and 42 as shown in FIGURE 6, the manner in which the bilateral switches 41 and 42 are synchronously driven will now be more fully explained. It will be appreciated that since tunnel diode TD₇ is normally in a low voltage state, transistor Q₇ is turned off and base drive is supplied through resistor R₂₀, diode D₁₇, to the base electrode of the transistor switch Q₆. Therefore, transistor switch Q₆ is normally in a closed position. Similarly, in bilateral switch 42 tunnel diode TD₈ is normally in a low voltage state. As a result, transistor Q₁₀ is turned off, and base drive is applied to the transistor Q₉ through the resistor R₂₂ and diode D₁₈. When transistor Q₉ is turned on, base drive is diverted from the base electrode of the transistor switch Q₈ and consequently, the transistor switch Q₈ is normally in the open position.

Referring again to bilateral switch 41, at the instant a negative pulse is induced across the secondary winding S₄, tunnel diode TD₇ is switched to its high voltage state causing base drive to be applied to the transistor Q₇. Thereupon, transistor Q₇ conducts and diverts base drive from the transistor switch Q₆. Consequently, transistor switch Q₆ is switched to the open position. At the same instant that a negative pulse is induced across the secondary winding S₄, a negative pulse is simultaneously induced across the secondary winding S₅ of the pulse transformer T₄. This negative pulse causes tunnel diode TD₈ to be switched into a high voltage state. As a result, base drive is applied at the base electrode of transistor Q₁₀. When transistor Q₁₀ conducts, base drive is diverted from transistor Q₉. As transistor Q₉ is switched off, base drive is applied to the transistor switch Q₈, and transistor switch Q₈ is switched to a closed position.

Bilateral switch 41 will remain in an open position and bilateral switch 42 will remain in a closed position until the tunnel diodes TD₇ and TD₈ are reset to their low voltage state. This occurs when a positive pulse is induced across the secondary windings S₄ and S₅. A positive pulse is induced across the secondary windings S₄ and S₅ when one of the tunnel diodes TD₅, TD₆ is switched to its low voltage state. Thus, as the feedback signal applied at the feedback control 43 varies in response to the change in the lamp current, the apparatus 40 is repetitively shifted from one switching mode to the other. In this manner, the energy supplied to the lamps 1, 2 is regulated and maintained dynamically to provide the energy for operating the lamps 1, 2.

From the foregoing description of the apparatus of the invention and its operation, it will be apparent that the power source is not disconnected from the lamp circuit in any of the modes of operation but is controllably varied in response to a feedback signal to provide the energy required for operation of the lamps. An advantage of the apparatus of the invention is that it is possible to achieve an appreciable reduction in the volt-amperes required in the system as compared with conventional passive ballasting systems and to accomplish this end with good regulation and stability.

Where a conventional ballast, such as a reactor, is used to ballast an electric discharge lamp, a supply voltage about 200 or 300 percent above the lamp operating voltage is generally required to provide the required ballasting characteristic. For example, if we take a fluorescent lamp that requires an operating voltage of 40 volts r.m.s., this lamp can be operated from a 120 volt, 60 cycle power supply. Let us assume in this case that a series ballasting reactor would be used to provide a voltage drop of approximately 110 volts. If we assume that this fluorescent lamp draws a load current of 1 ampere, the volt-ampere requirement of the series ballasting reactor would be approximately 110 volt-amperes. However, with the dynamic energy balancing arrangement of the present invention, it is possible to maintain satisfactory stability in the fluorescent lamp by operating the lamp from a supply voltage of 40 volts r.m.s. by dynamically varying the

voltage within 10 volts above or below the supply voltage. It will be understood, of course, in this instance that an auxiliary starting means would be provided to aid in starting the lamp. In such an apparatus the volt-ampere requirement would be about 10 volt-amperes. If the supply voltage varies as much as 10 percent, to provide a completely satisfactory operating point, the lamp may be operated from a 50 volt supply with a 20 volt variation above and below the supply voltage. In this case, the volt-ampere requirement would be 20 volt-amperes as contrasted with 110 volt-amperes required by a conventional ballast.

It will be noted that in the aforescribed embodiments of the invention, I have not shown any filament transformers for supplying filament heating current for the lamps. If electric discharge lamps employing cathodes that require a continuous supply of heating current are employed, it will be understood that a filament transformer may be used to supply the necessary heating current to maintain the electron emission at the cathodes. Also, it will be appreciated that starting aid circuits may be used in conjunction with the improved operating circuit arrangement of my invention to aid in initially starting the electric discharge lamp.

An important advantage of the arrangement of the present invention resides in its adaptability to control by means of feedback. Conventional ballasting systems are passive and current is dependent upon the electrical impedance of the electric discharge lamp. As an electric discharge lamp ages, the light output of the lamp appreciably diminishes. For example, when a conventional 60 cycle ballast is used to operate a fluorescent lamp, such as a 96 PG 17 power groove lamp, the light output of the lamp will diminish to approximately 70 percent of its original light output after 6000 hours of operation. With the present arrangement, it is possible to maintain the light output of electric discharge lamps at a substantially constant level during the normal life of the lamp. For example, if a light sensitive cell is used to provide a feedback signal to regulate the energy levels applied at the lamp, it is possible to operate the lamp in response to the light output of the fluorescent lamp and thereby dynamically balance the energy at the source with the energy required to operate the lamp at a substantially constant level for the normal life of the lamp. Although in the specific exemplifications of my invention I have used feedback arrangements sensing lamp current and the light output, it will be apparent that other quantities can be readily sensed by the feedback means to provide a basis for regulation and operation of the electric discharge lamp.

From the foregoing discussion of the advantages of the invention and the above description of the various exemplifications thereof, it is to be understood that many modifications may be made by those skilled in the art, without actually departing from the invention. It is, therefore, intended in the appended claims to cover all such equivalent variations that come within the true spirit and scope of my invention.

What I claim as new and desire to secure by Letters Patent of the United States is:

1. An apparatus for operating an electric discharge lamp from a power source, said apparatus comprising: a power source, an electric discharge lamp, a control means for varying the energy supplied to the electric discharge lamp by the power source, a feedback circuit coupled to said lamp for providing a feedback signal indicative of a lamp operating condition and coupled with said control means to activate said control means in response to said feedback signal, and circuit means including input leads for connection to the power source and including output leads for connection with the electric discharge lamp to supply the output of the apparatus to the lamp, said circuit means connecting said control means in circuit with said output leads and said

input leads, and said control means dynamically balancing the energy from the source with the energy required to control the operation of the electric discharge lamp by repetitively varying the energy supplied at said output leads from one predetermined level to another at a rate which varies as a function of the magnitude of current in said discharge lamp.

2. The apparatus set forth in claim 1 wherein said feedback circuit is connected in circuit with one of said output leads to supply a feedback signal to said control means that is functionally related to the lamp current.

3. An apparatus for operating at least one electric discharge lamp from a power source, said apparatus comprising: a power source, at least one electric discharge lamp, a control means for repetitively varying the voltage across said electric discharge lamp from one predetermined level to another, feedback circuit for providing a feedback signal indicative of a lamp operating condition and coupled to said lamp coupled with said control means for activating said control means in response to a feedback signal indicative of a lamp operating condition, and circuit means including input leads for connection to the power source and including output leads for connection with at least one electric discharge lamp to supply the output of the apparatus to the lamp, said circuit means connecting said control means in circuit with at least one of said output leads and one of said input leads to place said control means in series circuit relation with the lamp, and said control means dynamically balancing the voltage at the source with the voltage required to control the operation of the electric discharge lamp by repetitively varying the energy supplied at the output leads from said one predetermined level to another in response to and at a rate indicative of the magnitude of said feedback signal.

4. An apparatus for operating at least one electric discharge lamp from an alternating power source, said apparatus comprising: an alternating power source, at least one electric discharge lamp, at least one bilateral switch, means for repetitively driving said bilateral switch to a high impedance state and to a low impedance state in each half cycle of the alternating power source, an impedance element connected in shunt with said bilateral switch, circuit means including input leads for connection with the power source and output leads for connection with the electric discharge lamp to supply power from said power source to the lamp, said circuit means connecting said bilateral switch in circuit with at least one of said input leads and one of said output leads, said bilateral switch when driven from one of said impedance states to the other in each half cycle causing the energy supplied to said output leads to be changed from one level to a second level, said repetitive changing of said energy levels having a rate which varies as a function of the current drawn by said discharge lamp to dynamically balance the energy provided by said source with the energy required for operation of the electric discharge lamp.

5. A system for operating at least one electric discharge lamp from an alternating power source, said system comprising: an alternating power source, at least one electric discharge lamp, at least one bilateral switch, means for repetitively driving said bilateral switch to a high impedance state and to a low impedance state in each half cycle of the alternating power source, a first impedance element connected in shunt with said bilateral switch, an inductance connected in series circuit relation with said bilateral switch, circuit means including input leads for connection with the power source and output leads for connection with the electric discharge lamp to supply the output of the apparatus to the lamp, said circuit means connecting said bilateral switch in circuit with at least one of said input leads and one of said output leads, said bilateral switch when driven from one of said impedance states to the other in each half cycle causing the energy supplied to said output leads to be changed from one

level to a second level, a feedback device coupled to said lamp for indicating the energy utilized by said lamp, and means coupling said feedback device to said driving means for repetitively changing said energy levels at a rate proportional to the energy utilized by said lamp to vary the impedance of said inductance and dynamically balance the energy provided by said source with the energy required for operation of the electric discharge lamp.

6. A system for operating an electric discharge lamp from a power source, said system comprising: a power source, an electric discharge lamp, a switching means, driver means for repetitively driving said switching means to a high impedance state and to a low impedance state, a feedback circuit coupled to said lamp and to said driver means to activate said driver means in response to a feedback signal, an impedance element connected in shunt with said switching means, circuit means including input leads for connecting with the power source and output leads for connection with the lamp to supply the output of the apparatus to the lamp, said circuit means providing a path for the supply of energy from the power source to said lamp when the switching means is driven to a low impedance state and to provide a path for the supply of energy from the power source to the lamp through said impedance element when the switching means is driven to the high impedance state, said repetitive switching action of said switching means being at a rate responsive to said feedback signal to dynamically balance the energy at the source with the energy required for operation of the electric discharge lamp.

7. The system set forth in claim 6 wherein an inductive element is connected in series circuit relation with said switching means.

8. A system for operating an electric discharge lamp from an alternating supply, said system comprising: an alternating supply, an electric discharge lamp, a control means for controlling the power supplied to said electric discharge lamp, said control means including a bilateral switch, an impedance element connected in shunt therewith, a driver means coupled with said bilateral switch to repetitively activate said bilateral switch to a high impedance state and to a low impedance state during each half cycle of the alternating supply in response to a feedback signal that indicates the magnitude of power supplied to said lamp, said feedback signal controlling the switching rate of said switching means, circuit means including input leads for connection with the alternating supply and output leads for connection with the lamp to apply the output voltage across the lamp, said circuit means connecting said bilateral switch in circuit with one of said output leads and one of said input leads to provide a path for the supply of energy from the source to the lamp through said bilateral switch when said switch is in the low impedance state and to provide a path from the source to the lamp through said impedance element when said bilateral switch is in the high impedance state.

9. The system set forth in claim 8 wherein an inductor is included in series circuit relation with said bilateral switch to control the supply of energy to the lamp as a function of the switching time of said bilateral switch being activated from one state to the other.

10. A system for operating an electric lamp from an alternating power source, said system comprising: an electric lamp, a power source having a plurality of selectable voltages, control means including at least one transistor switch, circuit means including input leads for connection to said voltages of the power source and output leads for connection with the electric discharge lamp to supply operating voltage to the lamp, said circuit means connecting said control means in circuit with one of said input leads and one of said output leads, said transistor switch being repetitively connected to alternate input leads to cause the voltage applied across said output leads to instantaneously vary from one predetermined voltage

level to another at a rate which varies as a function of the magnitude of current in said lamp, said control means thereby dynamically balancing the energy at the power source in each half cycle of the alternating power source with the energy required for operation of the lamp.

11. The system set forth in claim 10 wherein a feedback circuit for providing a feedback signal indicative of a lamp operating condition is coupled to said lamp and to said voltage control means to activate said control means in response to a feedback signal.

12. An apparatus for operating an electric discharge lamp comprising: an alternating power source, an electric discharge lamp, a control means including a transistor switch and a driver means coupled to said transistor switch to control its switching action, circuit means including input leads for connection to the power source and including output leads for connection with the electric discharge lamp to supply the output of the apparatus thereto, said circuit means connecting said transistor switch in circuit with one of said output leads and one of said input leads, a light sensing means coupled with said driver means to activate said driver means to vary the impedance of said control means between first and second impedance levels in response to the light output of said lamp, said switching action of said transistor switch causing the current supplied at the output leads to vary from one current level to another, said control means switching between said first and second impedance level in each half cycle of the alternating power source to control the operation of the lamp.

13. The apparatus set forth in claim 12 wherein an inductor is included in series circuit relation with said transistor switch to control the rate of change of current supplied at the output leads between said current levels.

14. An apparatus for operating an electric discharge lamp, said apparatus comprising: a direct current source, an electric discharge lamp, input leads for connection to the direct current source, a pair of output leads for supplying the output of the apparatus to at least one electric discharge lamp, a switching transistor having an emitter, collector and base electrode, said emitter and collector electrodes being connected in circuit with one of said input leads and one of said output leads, circuit means connecting the other of said output leads in circuit with the other of said input leads, a driver means coupled with said switching transistor to activate said switching transistor between a high and low impedance state to vary the impedance in circuit with the electric discharge lamp thereby causing the current supplied at the output leads to vary from one current level to another, said driver means being driven in response to a lamp operating condition and said switching transistor being repetitively activated to operate said at least one electric discharge lamp between said current levels at a rate which varies as a function of the magnitude of current in said lamp.

15. The apparatus set forth in claim 14 wherein an impedance element is connected in series circuit relation with said switching transistor to control the rate of change of the current between said current levels.

16. An apparatus for operating at least one electric discharge lamp from a power source, said apparatus comprising: a power source, at least one electric discharge

lamp, a control means for repetitively varying the voltage across said electric discharge lamp from one predetermined level to another, a feedback circuit including a light sensing element disposed in proximity to said lamp to provide a feedback signal indicative of the operating condition of said lamp, means coupling said feedback circuit to said control means for activating said control means in response to said feedback signal and thereby activate said control means as a function of the light output of said electric discharge lamp, and circuit means including input leads for connection to the power source and including output leads for connection with at least one electric discharge lamp to supply the output of the apparatus to the lamp, said circuit means connecting said control means in circuit with at least one of said output leads and one of said input leads to place said control means in series circuit relation with the lamp, and said control means dynamically balancing the voltage at the source with the voltage required to control the operation of the electric discharge lamp by repetitively varying the energy supplied at the output leads from said one predetermined level to another in response to and at a rate indicative of the magnitude of said feedback signal.

17. An apparatus for operating at least one electric discharge lamp from an alternating power source, said apparatus comprising: an alternating current power source, at least one electric discharge lamp, at least one bilateral switch having an impedance element connected in shunt with said bilateral switch, means for repetitively driving said bilateral switch to a high impedance state and to a low impedance state, circuit means including input leads for connection with said power source and output leads for connection with said electric discharge lamp to supply power from said source to said lamp, said circuit means connecting said bilateral switch in circuit with at least one of said input leads and one of said output leads, said bilateral switch when driven from one of said impedance states to the other in each half cycle causing the energy supplied to said output leads to be changed from one level to a second level, the repetitive changing of said energy levels having a rate which varies as a function of the current drawn by said discharge lamp to dynamically balance the energy provided by said source with the energy required for operation of the electric discharge lamp, and a feedback circuit operatively coupled to said lamp and to said means for repetitively driving said bilateral switch to activate said switch in response to variations in the light output of said electric discharge lamp.
